[57] CLAIM

The ornamental design for a container, as shown and described.

DESCRIPTION

FIG. 1 is a right side elevational view of a container embodying my new design;

FIG. 2 is a top plan view thereof;

FIG. 3 is a bottom plan view thereof;

FIG. 4 is a front elevational view thereof;

FIG. 5 is a rear elevational view thereof;

FIG. 6 is a top perspective view of the bottle shown with the closure in an open position; and

FIG. 7 is a sectional view taken in the direction of the arrows on line VII-VII of FIG. 1.
